UNITED STATES PATENT OFFICE.

BYRON L. HEATER, OF FOREST PARK, ILLINOIS.

HANGER.

1,414,127.

Specification of Letters Patent. Patented Apr. 25, 1922.

Application filed August 30, 1920. Serial No. 407,013.

To all whom it may concern:

Be it known that I, BYRON L. HEATER, a citizen of the United States, residing at Forest Park, in the county of Cook and State of Illinois, have invented certain new and useful Improvements in Hangers, of which the following is a description.

My invention belongs to that general class of devices known as hangers, and relates particularly to a hanger designed for supporting trolley wires, cables and the like from suitable cross wires, or the equivalent. The invention has among its objects the production of a device of the kind described that is simple, convenient, durable, efficient and satisfactory for use wherever found applicable. More particularly it has as an object the production of a device which may be readily applied or removed, and which will securely hold the wire at the desired point. The same is also designed to reduce sparking, vibration and wear on the trolley wheel and trolley wire. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts,

Figure 1 is a side elevation of my improved hanger;

Figure 2 is a similar view showing the device partly disassembled;

Figure 3 is a sectional view taken substantially on line 3—3 of Figure 4;

Figure 4 is a sectional view taken substantially on line 4—4 of Figure 7;

Figure 5 is an end elevation, the trolley wire shown in section;

Figure 6 is a sectional view taken substantially on line 6—6 of Figure 7; and

Figure 7 is a top plan view.

Inasmuch as my device is particularly intended for supporting trolley wires or the like, I shall describe the same in that connection, 1 representing the trolley wire and 2 the cross wires which are arranged to carry the trolley wire above the tracks. My device is designed to operatively connect the trolley wire to the cross wires so that the

same is securely carried and supported at all times. The device consists of cooperating parts 3 and 4, the part 3 being designed to be carried by the cross wire 2 and part 4 being arranged to engage and carry the trolley wire and to be supported by the part 3. The cooperating part 3 is provided with a projecting part 5 at one side which may, if desired, extend entirely around the part 65 forming substantially a flange, as shown in the figures. The same is also provided with extending prongs or parts 6 at each side which are preferably bent as indicated at 7 and thence extend laterally as shown at 8, 70 or in an equivalent manner, so that the same substantially parallels the extending parts 6. Part 3 is extended at its ends as at 9 and is chambered as shown at 10, the lower portion 9 being elongated so as to overlie the 75 trolley wire for a distance.

The part 4 is provided with the groove 12 which, as most clearly shown in Figure 4, is formed with a substantially sharp ridge, cusp or hump 13 intermediate the ends, the 80 groove terminating at each end substantially flush with the under side of the part, so that when the wire is positioned in the groove and the device secured, the under side of the trolley wire and the under side of the part 85 4 at each end will be in alignment. It will be noted that a vertical plane drawn through the groove, cutting both ends, would pass through the axis of the shank, and that the groove has an opening thereto leading from 90 one side of the member 4. A lip 14, however, is formed so that the wire 1 is securely held in the groove. It will be noted by referring to Figure 6 that part 4 is formed at an angle or tapered at the bottom so that 95 it substantially is of the same contour as the trolley wire, so that when a trolley wheel runs over the same, there will be no jump or vibration. Part 4 is constructed with the part 15 fitting the recess or chamber 10 and 100 extended to provide a shank 16, parts 3 and 4 being secured together by a nut 17 or equivalent means, engaging the shank and locking the parts together. Obviously, a lock nut or lock washer may be provided to 105 lock the nut 17 in place, or a castellated nut may be provided.

It will be particularly noted in referring to the drawings that the parts 3 and 4 are so formed as to taper down to the wire at 110 the top and bottom and at the sides, so that as before mentioned, the trolley wheel run-

ning in engagement with the wire, will run smoothly over the hanger.

In use the cooperating part 3 may be secured to the cross wire 2, as shown in the figures, said wire lying between the projections 5 and 6 and bent downwardly and outwardly at both sides so as to project through the hooks or prongs 7-8, after which the wire 1 may be inserted in the groove 12 and the shank inserted through the opening in the part 3. The nut 17, or its equivalent, may then be applied as indicated in Figure 2, and the part 4 drawn in place, as shown in Figure 1. As the part is drawn up, the trolley wire 1 will be crimped substantially as indicated in Figure 4. Of course, if desired, the parts 3 and 4 may be secured together with the trolley wire in place prior to the attaching of part 3 to the cross wire, 20 this being immaterial so far as the use of the device is concerned.

It will thus be seen that the device may be easily and quickly applied or removed, that it is simple, consisting of only a few parts, and consequently may be economically manufactured. The wire is not only securely supported but is substantially entirely closed in and locked in place. In case the part 4 wears to any extent it may be renewed without renewing the complete hanger. The trolley wire may be easily renewed, as the same may be quickly detached from the hangers and a new wire arranged in place. The hanger will not slip or slide 35 on the cross wires and neither will the trolley wire slip or slide in the hanger. In this connection it may be mentioned that the recess or groove 12 and the inner face of the part 3 where the same comes in contact with 40 the trolley may be roughened or otherwise constructed to slightly bite into the trolley wire and firmly grip the same. This is particularly desirable where it might be desired to splice a trolley wire at one of the hangers. 45 With my device there is a reduction, if not a complete elimination, of sparking, there are no projecting parts which will cause a hammering or striking of the trolley wheel, thereby causing injury and vibration. In 50 case of wearing the part 4, there is but slight danger of the same wearing to an extent where the trolley wire would be accidentally released, and should there be wear it is readily noticeable and a new part 4 may be 55 quickly and easily installed. By reversing the device the hanger is particularly adapted for supporting cables employed for tracks

for carriers and the like as there are no projecting parts to cause hammering or vibration, a straight continuous track being secured.

Having thus described my invention, it is obvious that various immaterial modifications may be made in the same without departing from the spirit of my invention; 65 hence I do not wish to be understood as limiting myself to the exact form, construction, arrangement and combination of parts herein shown and described, or uses mentioned.

What I claim as new and desire to secure 70 by Letters Patent is:

1. In a hanger of the kind described, in combination, a part arranged to engage a member to be carried, and a cooperating part for supporting the first mentioned part, and 75 provided with a pair of spaced flanges and a pair of hooks therebelow at each side thereof, whereby said cooperating part may interengage a suitable wire support.

2. In a hanger of the kind described, in 80 combination, a part arranged to engage a member to be carried, and a cooperating part for supporting the first mentioned part, and provided with a pair of hooks therebelow at each side thereof, the seats of said hooks 85 being intermediate the sides of said part, whereby said cooperating part may engage a suitable wire support, said wire support being engaged between said flanges and extended rearwardly and downwardly to said 90 hooks and outwardly through said hooks at both sides.

3. In a hanger of the kind described and in combination, a part arranged with a longitudinal wire-engaging groove of a size to 95 receive and closely fit the wire to be hung, said groove having an entrance thereto leading from one side of said part and having a sharp cusp intermediate its ends, said part having a shank portion, a cooperating part 100 for supporting said part, said second part mounted on said shank and covering said groove to clamp said wire in place, and means on said second part for interengaging with and being rigidly supported by a single 105 supporting wire.

In testimony whereof, I have hereunto signed my name in the presence of two subscribing witnesses.

BYRON L. HEATER.
